UNITED STATES PATENT OFFICE.

GARDNER M. SHERMAN, OF SPRINGFIELD, MASSACHUSETTS.

TOBACCO-MOISTENING DEVICE.

SPECIFICATION forming part of Letters Patent No. 469,001, dated February 16, 1892.

Application filed February 16, 1891. Serial No. 381,631. (No model.)

To all whom it may concern.

Be it known that I, GARDNER M. SHERMAN, a citizen of the United States, residing at Springfield, in the county of Hampden and 5 State of Massachusetts, have invented new and useful Improvements in Moistening Devices for Cigar and Tobacco Receptacles, of which the following is a specification.

The object of this invention is to provide 10 for boxes, cases, or other inclosures for cigars or tobacco or products thereof means for maintaining the cigars or tobacco, &c., in a suitably moist condition.

The invention consists in the construction 15 and combination of parts, substantially as will hereinafter more fully appear, and be set forth in the claims.

Referring to the accompanying drawings, in which embodiments of this invention are 20 shown, Figure 1 is a central vertical section of a jar or case for cigars equipped with moistening devices. Fig. 2 is a plan view of the under side of the cover of the jar or case. Fig. 3 is an under side view of a cast or absorbent body employed. Fig. 4 is a perspective view in detail of a part of the register hereinafter more particularly referred to.

In the drawings, A represents a receptacle for cigars, preferably, as shown, in the form 25 of a jar having a screw-threaded neck, with which engages the cap a.

B represents the supplemental chamber for containing the absorbent material, and it is shown as at the top of the receptacle A, such 35 location being deemed much the preferable one.

d represents a port or opening, which leads 40 through the stock or material which constitutes the partition between the supplemental chamber B and the interior of the main receptacle A, one or more of said openings d being provided, as the judgment of the constructor may dictate.

D represents a register having therein one 45 or more ports or openings f, and said register is supported on the part of the apparatus which constitutes the partition between the main and supplemental chambers and is movable, so that the port or ports thereof may be 50 brought into or carried out of coincidence with the said apertures d.

G represents a suitable body or portion of

absorbent material for holding the water or other moistening-liquid employed. This absorbent body usually consists of a plaster 55 cast, although asbestos, sponge, or vegetable matter may be made use of as the moisture-absorbent, and so far as certain features of the invention are concerned they are not in any manner to be limited to an absorbent 60 body, for the supplemental chamber B may of itself be constituted to contain water or other moistening-liquid or to receive and inclose an independent holder therefor. Of course, however, an absorbent material substantially 65 as described is much to be preferred, for the reason that a maximum moistening-surface and freer circulation are insured. The supplemental chamber is preferably in the form of a cylindrical casing of thin metal 70 and is secured to the cover of the main receptacle A in any efficient manner, as by riveting or by soldering, screw-engaging, or otherwise connecting. The supplemental chamber is shown as located above the cover and outside 75 of the cigar case or box as the preferred location therefor.

As shown in the drawings, the supplemental chamber and absorbent-receptacle B is constituted by the cup-like part 10, having 80 the bottom closed with the exception of the ports d and by its bottom riveted to the spun metallic screw-cap of the jar-cap a. Said cup part 10 is open at its top and receives the struck-up metal cover 12, whereby to insert 85 the moistened cast or absorbent G or to remove the same for the remoistening thereof.

The register D (here shown, and particularly in perspective in Fig. 4) consists of the disk 14, adapted to lie closely under the under 90 and inner sides of the jar-cap a, being held to confinement thereat and so that it may rotate by the stud 15, which passes through the jar-cap a and the bottom of the cup 10, being riveted or upset at its extremity. This register is provided with a knurled thumb-knob 95 16, whereby to conveniently turn the said register into and out of coincidence with the ports d, which may be desired for insuring a greater or less freedom of the circulation of 100 the moisture down and into the jar, such regulation being accomplished, as will be entirely apparent, on the removal of the cap.

The cast is preferably, and substantially as

shown in Figs. 1 and 3, recessed or apertured, so as to leave increased moistening-surface and to insure an efficient circulation within the supplemental chamber, it being noted especially that the recessed portion of the cast is that which is adjacent the ports or passages leading from the one chamber to the other. The absorbent body contained in the supplemental chamber may be saturated with a flavoring or odorizing liquid or material, so that the cigars may be correspondingly scented or flavored.

In Fig. 1 is shown an upturned lip *u* in the bottom of the chamber *B*, surrounding the ports *d d*, so that water which may settle from the absorbent will be prevented from falling in substantial quantities into the cigar-holding chamber.

What I claim as my invention is—

20 1. The combination, with the receptacle for tobacco or cigars, of a supplemental chamber

having perforations communicating with said receptacle, an upturned lip, as *u*, in the bottom of said chamber, and an absorbent material in said chamber, substantially as and for the purpose set forth.

2. The combination, with a receptacle or jar and a cap *a* for closing the same, having the perforations through its top, and a box formed of metal or other impervious material mounted on the top of the jar-cap and an absorbent material therein, of a cover for closing said box and openings *d* in the bottom of the box, the movable disk *14*, having the perforations *ff*, the stud *15*, and the thumb-knob *16*, all arranged for operation substantially as described and shown, and for the purpose set forth.

GARDNER M. SHERMAN.
